UNITED STATES PATENT OFFICE.

HENRY HENDRICKS, OF ALTON, ILLINOIS, ASSIGNOR OF ONE-HALF TO FRED R. HENDRICKS, OF ALTON, ILLINOIS.

ROTARY GASOLENE-ENGINE.

1,034,451.

Specification of Letters Patent.

Patented Aug. 6, 1912.

Application filed April 22, 1911. Serial No. 622,666.

To all whom it may concern:

Be it known that I, HENRY HENDRICKS, a citizen of the United States, and resident of Alton, Madison county, Illinois, have invented certain new and useful Improvements in Rotary Gasolene-Engines, of which the following is a specification containing a full, clear, and exact description, reference being had to the accompanying drawings, forming a part hereof.

My invention relates to an improved rotary gasoline engine, and consists in the novel construction and arrangement of parts hereinafter specified and claimed.

The object of my invention is to provide a more efficient and simplified construction in rotary engines; and further to provide a rotary engine which shall be light and simple, as well as devoid of any objectionable vibration.

In the drawings: Figure 1 is a sectional side elevation of a rotary engine embodying my invention, the section being taken on line 1—1 of Fig. 2; Fig. 2 is a sectional front elevation of my engine, the section being taken on line 2—2 of Fig. 1; Fig. 3 is a sectional side elevation similar to Fig. 2, but with the parts in a different relative position; and Fig. 4 is an inverted plan view of the segmental piston detached, looking at the same in the direction indicated by the arrow 4 of Fig. 3; Figs. 5 and 6 are detail views of the electrical connections.

The numeral 1, indicates a fixed cylindrical casing having the usual supporting brackets 2, by means of which latter the engine may be supported by the frame work of an automobile, aeroplane, or in any suitable location to which it may be adapted.

Within said casing 1, all of the rotating parts are mounted to revolve. Within said casing 1 is a revolving cylinder 3, which may be called the annular cylinder, because it has a circular bore 4 in which vibrates the segmental piston 5. Mounted in suitable bearings 6, in the said revolving cylinder 3 is a crankshaft 7 having crank 8, to which is connected one end of the connecting rod 9, the opposite end of said connecting rod being mounted on a piston-pin 10 carried by said segmental piston 5, so that when said piston vibrates in its cylinder it will make regular "strokes" therein, and the said crank-shaft will make corresponding revolutions in its bearings. The

said revolving cylinder 3, is fixed upon the main-shaft 11 by means of keys 12, and said main-shaft revolves in the bearings 13 carried by the opposite heads of the said casing 1. Said casing is preferably made, as shown, in two mating sections, the meeting edges of which are rabbeted together at 14 to make a tight-joint and the sections are secured by means of screws, or bolts 15, passing through one section and engaging the opposite section. Said bolts 15 are spaced apart and disposed near the periphery of the said sections.

It is obvious that a "sun and planet" type of gearing must be employed for connecting the crank-shaft 7 to the fixed casing 1. It is further obvious that the gearing may be located at one end or it may be duplicated, so a sun and planet gearing will be located at each end of said crank-shaft. This latter is the construction which I prefer and have illustrated. By duplicating the gearing at each end of the crankshaft, I equally distribute the strain at each end of said crank-shaft and apply the power equally to both of the heads of the revolving cylinder 3, and thereby revolve the main-shaft 11.

16 indicates gear wheels which are fixed by means of screws 17 to the inner face of the opposite sections of the casing 1, so that the main-shaft 11 revolves within said gear wheels, and the crank-shaft gear wheels 18 being of the same size and pitch as said gear wheels 16, are fixed upon said crank-shaft by means of keys 19, and revolve with said crank-shaft and simultaneously rotate around the said fixed gear wheels 16. (See Fig. 1.)

The revolving cylinder 3 is preferably composed of two mating sections, the meeting edges of which are provided with rabbets 14, similar to those of the sections of the casing 1, and the two sections of the said cylinder are secured together by bolts 20. The said piston 5 is provided with an integral neck 21, which connects it to its hub 22, which latter is mounted loosely to rock on the main-shaft 11. The said main-shaft 11 is provided at one end with an axial bore 23, the outer end of which is closed by a plug 24. Lateral openings 25 and 26 are formed in the main-shaft and communicate with the said axial bore 23. The outer lateral opening 25 communicates, 115

at all times, with an annular passage 27, formed in the adjacent bearing 13, and the threaded connection 28 is provided for the accommodation of a carbureter so that a proper "mixture" of gas and air may be fed to the engine. Any well known form of carbureter may be employed. By means of the annular passage 27, communication between the carbureter connection 28 and the axial bore 23 is maintained at all times. From the axial bore 23 of the main-shaft the mixture passes by way of the lateral opening 26 into a recess 29 formed in the piston hub 22, and from thence passes directly into the crank space of the bore 4 of the annular revolving cylinder 3. (See Figs. 2 and 3.)

The numeral 30 indicates a lateral groove or cut-away portion in the piston hub 22, for the purpose of permitting the crank end of the connecting rod 9 to pass said head during operation of the engine.

31 indicates a circular abutment provided with a common packing ring 32 and fixed—being set within a common groove—in the cylinder bore 4, so as to act as the fixed "end" of the cylinder and permitting the charge of gas from the crank case to be compressed and fired within the space between the free end of the piston 5 and the said circular abutment 31. Although the abutment 32 does not move, yet I have found it necessary to provide it with a packing ring for the purpose of preventing leakage past its periphery.

33 indicates the induction port, by means of which the mixture may pass into the compressing and firing space of the cylinder, and 34 indicates the exhaust port which is located in the wall of the cylinder almost diametrically opposite the induction port 33.

The space in which the crank-shaft and connecting rod are located in the cylinder 3, may be called, the "crank case" and will be hereinafter so called.

At this point I would state that my improved rotary engine is preferably constructed to operate upon what is known as the "two cycle" principle. The piston 5 is provided with the usual packing rings 35 and the deflector 36. The usual electrical sparking coil and battery or other source of electricity, are made use of. A common spark plug 37 is inserted in an aperture 38 in the wall of the revolving cylinder 3, so that its spark points will project into the space between the end of the piston which carries the said deflector 36 and the circular abutment 31, to explode the charge in said space at the proper time. (See Fig. 6.)

Of course it is necessary to provide a suitable mechanism for making electrical contact with said spark plug during the rotation of the cylinder, and in the drawing I have illustrated one form of such appa-

ratus, which I will now proceed to describe. Carried upon the exterior of the revolving cylinder 3, at a point closely adjacent the spark plug 37, is a metallic contact 39, which is insulated from the cylinder by a block of insulation 40, recessed in the outer wall of said cylinder. The contact 39 is connected to the spark plug 37 by suitable wire 41. Fixed upon the outer wall of the casing 1, but insulated therefrom, is a bracket 42, which supports the outer end of the contact pin 43. The said contact pin projects through an aperture in the wall of the casing 1, but is insulated therefrom by ferrule 44 and the inner end of said contact pin is beveled, or rounded, at 45 so that it may readily contact with and pass over the contact plate 39. The spring 46 is coiled about the outer end of the said contact pin 43, so that the inner end of said spring will engage a collar 47 on said pin, while the outer end of said spring engages said bracket 42, to normally urge the said pin toward said sail contact 39. Current from the battery and spark coil (not shown) is conveyed to said contact pin through a flat spring 48, thereby permitting the said pin to slightly reciprocate in its bearings while its inner end is being engaged by and disengaged from the said contact 39.

My engine may be cooled by any common form of air or water cooling devices. The cooling water or air can be forced into the space between the revolving cylinder 3 and its casing 1, and make its exit through the exhaust opening 50; or it may be injected thereat and educted at any other desired point. In some instances the casing 1 may be cut away almost entirely, thereby leaving only a common frame to support the parts which require a fixed support. In case of an air cooled engine the omission of the casing 1, would, of course, permit the cylinder 3 to rotate in the open air and so would be effectively and satisfactorily cooled, especially if it were provided with the well known cooling "ribs".

The operation is as follows: The revolving cylinder and all parts carried thereby rotate in the direction indicated by the arrows in Fig. 3, that is toward the left hand. The direction of the outward stroke of the piston 5 is indicated by the arrow 49, in Fig. 2. With the parts in position as they are shown in Fig. 3, a charge of gas has previously been compressed in the "crank case" by the previous outward stroke of the piston 5, and the said charge rushes through the port 33 into the explosion chamber between the end of the piston and the adjacent abutment 31, striking the deflector 36 and thereby being thrown toward the said abutment, and at the same time "scavenging" the cylinder and driving out any remnants of the previous combustion through

the exhaust port 34, which latter is now opposite the exhaust opening 50 at the bottom of the casing. It will be understood that a suitable exhaust pipe can be connected by any skilled workman to the said exhaust opening 50. The engine is of course started in the usual manner by turning the main-shaft 11, which may be done by the usual starting crank. The charge is compressed by the piston 5 moving toward the abutment 31, which it will do until it reaches the position in which it is shown in Fig. 2, at which point the charge will be fully compressed, and will be ignited by the spark from the spark plug 37; as soon as the charge has been ignited the piston 5 will, of course, be forced outwardly away from the abutment 31 in the direction of the arrow 49, and the connecting rod 9 will of course revolve the crank-shaft 7 in the direction indicated by the arrow, and the motion of the crank-shaft will rotate the "planet" gear wheels 18 around the fixed gear wheels 16, and thereby rotate the cylinder and main-shaft. Continuous rotation of the parts will take place as the piston is vibrated by the consecutive explosions.

What I claim is:

1. The improved rotary engine herein described, comprising a fixed support, a main-shaft mounted in bearings on said support, a circularly-bored revoluble cylinder fixed to said main-shaft, a crank-shaft mounted in bearings in said cylinder to rotate therein and therewith, a segmental piston arranged to vibrate within the circular bore of said cylinder, a connecting-rod connecting said piston to said crank-shaft, an abutment fixed within said circular bore of said cylinder to

form a pressure generating chamber in the 40 annular space between said piston and said abutment; suitable means for admitting gas to said pressure-chamber while said cylinder is moving; means for exhausting the waste gases from said pressure chamber, and gear- 45 ing which connects said crank-shaft to said fixed support.

2. The improved rotary-engine, comprising a fixed support, a main-shaft mounted in bearings on said support, a circularly-bored revoluble-cylinder fixed to said main-shaft, a crank-shaft mounted in bearings in said cylinder to rotate therein and therewith, a segmental piston arranged to vibrate within the circular bore of said cylinder, a 50 connecting-rod connecting said piston to said crank-shaft, an abutment fixed within said circular bore of said cylinder to form a pressure generating-chamber in the annular space between said piston and said 55 abutment; suitable means for admitting gas to said pressure-chamber while said cylinder is moving; means for exhausting the waste gases from said pressure-chamber, gearing which connects said crank-shaft to 60 65 said fixed support, a sparking-device rotatable with said cylinder, and stationary means for making contact with said sparking-device and causing it to emit a spark as it rotates. 70

In testimony whereof, I have signed my name to this specification, in presence of two subscribing witnesses.

HENRY HENDRICKS.
